INVENTOR.

S. B. MORISON

BY
Hazard E. Miller
ATTORNEY.

UNITED STATES PATENT OFFICE.

SAMUEL BENJAMIN MORISON, OF REDLANDS, CALIFORNIA.

FRUIT-PICKER.

1,336,648.

Specification of Letters Patent. Patented Apr. 13, 1920.

Application filed July 2, 1919. Serial No. 308,238.

To all whom it may concern:

Be it known that I, SAMUEL BENJAMIN MORISON, a citizen of the United States, residing at Redlands, in the county of San Bernardino and State of California, have invented new and useful Improvements in Fruit-Pickers, of which the following is a specification.

My object is to make an improved fruit picker, and my invention consists of the novel features herein shown, described and claimed.

Figure 1 is a fragmentary perspective of a fruit picker embodying the principles of my invention.

Fig. 2 is a fragmentary bottom plan view upon an enlarged scale and shows the fingers and cutter, the view being taken looking in the direction indicated by the arrow 2 in Figs. 1 and 3.

Fig. 3 is a fragmentary edge view looking in the direction indicated by the arrow 3 in Fig. 2.

Fig. 4 is a fragmentary side elevation of the operating handles as seen looking in the direction indicated by the arrow 4 in Fig. 1.

Fig. 5 is a cross section on the line 5—5 of Fig. 4.

Fig. 6 is a cross section on the line 6—6 of Fig. 4.

Fig. 7 is a sectional detail on the line 7—7 of Fig. 2 and shows the operation of cutting the stem of an orange.

The main supporting handle 1 is a more or less long rectangular stick of wood having grooves 2 and 3 in the edge faces near its lower end and having its inner face hollowed out to make a track for the fruit. The sliding handle 4 is a short stick of the same material and fits against one side of the main handle 1 adjacent to the grooves 2 and 3. Metal clips 5 and 6 fit against the outer three sides of the sliding handle 4 near its ends and are held in place by nails or screws 7 and 8, and the edges of the clips 5 and 6 extend half way across the edges of the main handle 1 and have flanges 9 and 10 bent inwardly and operate in the grooves 2 and 3 so that the handle 4 is slidably connected to the handle 1 and adapted for reciprocation endwise to the extent of the grooves 2 and 3.

A groove 11 extends from the upper end of the groove 2 to the upper end of the handle 1. A piece of small tubing 12 fits in the groove 11 and is held in place by staples 13

embracing the tube and driven into the wood. A piece of hard tempered wire 14 is slidably guided through the tube 12 and the lower end of the wire has a hook 15 passing through the corner of the clip 5, so that as the handle 4 is reciprocated the wire 14 is reciprocated through the tube 12. The wire 14 is longer at both ends than the tube 12, the tube simply serving as a guide and bearing for the wire where it turns to a transverse position.

An attaching plate 16 is secured to the side face of the upper end of the handle 1 by rivets, the head 17 is formed integral with the upper end of the plate 16, the metal loop 18 is formed integral with the head 17 and braces 19 and 20 connect the attaching plate 16 to the loop 18 on each side of the head 17. The cloth sack or conducting tube 21 is attached to the loop 18, the loop 18 serving to hold the upper end of the sack open to receive the fruit one at a time.

Guide fingers 22 and 23 extend from the head 17 over the opening 24 formed by the loop 18. A housing plate 25 fits against the lower face of the fingers 22 and 23. A rigid cutting plate 26 fits between the housing plate 25 and the finger 22 and is held in place by screws 27 and 28 inserted through the housing plate 25 and through the cutting plate 26 and through the fingers 22. A pivoted cutting plate 29 fits between the housing plate 25 and the fingers 23 and has an operating arm 30 extending below the lower edge of the housing plate 25 inside of the head 17 and is held in place by a screw 31 inserted through the housing plate 25 through the cutting plate 29 and through the head 17. The lower end of the arm 30 is connected with the upper end of the wire 14 so that as the handle 4 is reciprocated the cutting plate 29 is operated.

An opening 32 is formed at the junction of the fingers 22 and 23 with the head 17 to receive the stem of the fruit and the space 33 between the outer ends of the fingers 22 and 23 leads to the opening 32. The cutting plates 26 and 29 have cutting edges 34 and 35 working in opposition and meeting to cut the stems of the fruit.

In the practical operation the fruit picker is manipulated to reach up to the orange or the like and guide it so that the fruit will pass under the head 17 with the stem passing through the opening 33 and guided by the fingers into the opening 32, and then the

handle 4 is pulled downwardly to operate the cutting edge 35 toward the cutting edge 34 to cut the stem and drop the orange or the like into the tube 21.

- 5 The housing plate 25 is made thin and the cutting edges 34 and 35 are near to the outer contacting face of the housing plate 25 so that the stem of the orange or the like may be severed close to the fruit and the fruit
- 10 will drop through the opening 24 into the conducting tube 21 and pass downwardly to be discharged from the lower end of the tube when desired without damaging the fruit.
- 15 Referring to Fig. 7, the cutting edges 34 and 35 are dished downwardly so that when the plate 25 fits against the bulge 36 of the orange around the stem 37 the cutting edges will extend downwardly into the depression 38 around the stem and cut the stem below the plane of the bulge 36, so that the stem will not project beyond the face 39 of the orange, and at the same time the plate 25 bearing upon the bulge 36 around the stem 25 avoids all liability of the cutting edges abrading the skin of the orange. A circular opening 40 is formed between the fingers 22 and 23 so as to make a bearing face extending nearly around the stem of the orange within which the cutting edges 34 and 35 operate. The plate 25 forms the lower face of the fingers around the opening 40.
- 30

Thus I have made a fruit picker which will cut the stems close to the fruit, which

will not cut or injure the fruit, which will easily reach much of the highest fruit without the use of a ladder, which will readily enable the operator to select and cut one orange or the like at a time, and which is 40 simply and easily made and easily operated.

Various changes may be made without departing from the spirit of my invention as claimed.

I claim:

1. A fruit picker comprising a main handle; a sliding handle attached to the main handle; a head attached to the main handle; a loop attached to the head; a cloth conducting tube attached to the loop; fingers extending from the head over the opening of the loop; a rigid cutting jaw mounted below the fingers; a pivoted cutting jaw mounted below the fingers in opposition to the rigid cutting jaw; and a connection between the sliding handle and the pivoted cutting jaw. 45

2. In a fruit picker, a handle; a loop rigid with the upper end of the handle; a conducting tube connected to the loop and held open 60 by the loop; fingers extending from the loop at right angles to the handle; a cutter mounted below the fingers; a wire connected to the cutter and extending down the handle; and means for operating the wire to operate the 65 cutter.

In testimony whereof I have signed my name to this specification.

SAMUEL BENJAMIN MORISON.
